(57) **CLAIM**

The ornamental design for a hanger clip for stairway spindles & balusters, as shown and described.

DESCRIPTION

FIG. 1 is a front, right perspective view of the first embodiment of a hanger clip for stairway spindles & balusters;

FIG. 2 is a rear, right perspective view thereof;

FIG. 3 is a top view thereof;

FIG. 4 is a left side view thereof;

FIG. 5 is a front view thereof;

FIG. 6 is a right side view thereof;

FIG. 7 is a bottom view thereof;

FIG. 8 is a back view thereof;

FIG. 9 is an environmental front, right perspective view of the hanger clip for stairway spindles & balusters thereof;

FIG. 10 is an alternate environmental front, right perspective view of the hanger clip for stairway spindles & balusters thereof;

FIG. 11 is a front, right perspective view of the second embodiment of a hanger clip for stairway spindles & balusters;

FIG. 12 is a rear, right perspective view thereof;

FIG. 13 is a top view thereof;

FIG. 14 is a left side view thereof;

FIG. 15 is a front view thereof;

FIG. 16 is a right side view thereof;

FIG. 17 is a bottom view thereof;

FIG. 18 is a back view thereof;

FIG. 19 is an environmental front, right perspective view of the hanger clip for stairway spindles & balusters thereof; and,

FIG. 20 is an alternate environmental front, right perspective view of the hanger clip for stairway spindles & balusters thereof.

The broken lines rendered in FIGS. 9, 10, 19 and 20 illustrates the environment of the claimed design and forms no part thereof.

1 Claim, 6 Drawing Sheets
